Attorney

UNITED STATES PATENT OFFICE.

HERBERT W. WOLFF, OF CHICAGO, ILLINOIS, ASSIGNOR TO AMERICAN CAR AND FOUNDRY COMPANY, OF NEW YORK, N. Y., A CORPORATION OF NEW JERSEY.

INTERLOCKING SPRING-PLANK.

1,336,458.

Specification of Letters Patent. Patented Apr. 13, 1920.

Application filed April 16, 1919. Serial No. 290,445.

To all whom it may concern:

Be it known that I, HERBERT W. WOLFF, residing at Chicago, county of Cook, State of Illinois, and being a citizen of the United States, have invented certain new and useful Improvements in Interlocking Spring-Planks, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

20 In said drawings:

Figure 1 is a side elevational view of a truck side frame equipped with the present invention, showing in section a body bolster and spring plank, the section thereof being taken on line 1—1 of Fig. 3;

Fig. 2 is a sectional plan view, the section being taken on line 2—2 of Fig. 1;

Fig. 3 is a vertical sectional view, the section being taken on line 3—3 of Fig. 1; and

Fig. 4 is a fragmentary detail view of a portion of the bottom member of the truck side frame of Fig. 1.

The object of the invention is to provide means adapted to prevent sidewise movement of spring planks in railway trucks of the type illustrated in the drawing in which there is a central opening for the insertion of the body bolster, springs, spring seat and spring plank, which opening is wider near the bottom than at the top so as to facilitate the entrance of body bolsters with attached column guides. The body bolster is moved upwardly to the position indicated in the drawing where it rests upon the conventional spring seat and spring, which are positioned above the spring plank.

As the necessary width of the spring plank is determined by the width of the body bolster and its supporting springs in truck side frames of the type illustrated, there is a space at each side of the spring plank between the truck columns and the spring plank. Various means have been provided for anchoring the spring plank in

position, many of which are difficult of application and to provide means to facilitate the assembly of the parts, the present invention contemplates features of novelty all as hereinafter more fully described and specifically pointed out in the claims.

Referring to the drawing, 5 indicates the truck side frame, 6 the central opening hereinafter referred to, 7 the truck bolster, 8 the springs, 9 the spring seat, 10 the spring cap, 11 the web of the channel-shaped spring plank, the normal plane of which web is horizontal in service, 12 a stop secured to said web 11 by suitable rivet or other connection, and 13 lugs cast integral with the side frame 5 and projecting laterally inwardly therefrom, as best shown in Fig. 2.

The lugs 13 are disposed, as shown in the drawing, in a plane below the web 11 of the channel-shaped spring plank and the stop 12 rests in the position between said lugs 13 so that with a lug 13 at each side of the stop 12 the spring plank cannot move sidewise in the opening 6 when the parts are assembled, as shown in Figs. 1 and 3. The stop portion 12, depending below the normal plane of the web of the spring plank, also serves as a spacing means for the truck side frames and it is understood that the parts illustrated are duplicated at the opposite side of the truck.

There is an advantage in providing the lugs 13, extending laterally inwardly from the truck side frame, as shown, because such disposition of the lugs permits the use of a spring plank of the conventional channel form with stops, as 12, or their equivalent, positioned as shown, and this arrangement permits the use of a spring plank, the web of which is not weakened by holes punched therein to interlock with vertically extending members adapted to pass through the web of said spring plank; neither is it necessary to perforate its vertical flanges for bolts adapted to secure such flanges to vertical members of the truck side frame.

What I claim is:

1. In combination, a channel-shaped spring plank provided with a portion depending below the normal plane of its web, a truck side frame provided with a central opening wider than said spring plank, and integral lugs extending laterally from said side frame to interlock with the spring plank.

2. In combination, a truck side frame having a central opening, a spring plank extending into and being of less width than the opening and having a depending portion, and means on the side frame adapted to engage with said depending portion to prevent sidewise movement of said spring plank.

3. In combination, a spring plank having a web portion and a portion depending below the normal plane of said web, and a truck side frame provided with a central opening wider than said spring plank and with integral laterally extending means adapted to interlock with the depending portion of the spring plank to prevent sidewise movement of the latter.

4. A cast metal truck side frame provided with a central opening and having integral lugs extending laterally therefrom, in combination with a channel-shaped spring plank having a web portion of less width than the width of said opening and having a portion depending below the normal plane of said web into the plane of said lugs to interlock therewith and prevent sidewise movement of the spring plank in said opening of the side frame.

In witness whereof I have hereunto set my hand in the presence of two witnesses. 30

HERBERT W. WOLFF.

Witnesses:

C. D. TERRELL,
MARY E. GALVIN.
